COMBINED FILING SPINDLE, GUARD, AND PUNCH

George L. Gilbert, Kalamazoo, Mich., assignor to Ralph G. Wenham and Maurice E. Follett, both of Kalamazoo, Mich.

Application June 16, 1947, Serial No. 754,995

3 Claims. (Cl. 129—7)

1

This invention relates to improvements in a combined filing spindle, guard and punch.

The main objects of this invention are:

First, to provide a combined filing spindle and guard therefor and punch which is easily manipulated to and from guard position, the guard being effectively supported as a punch head.

Second, to provide a structure having these advantages which is very economical in its parts and in the assembly thereof and at the same time strong and durable.

Further objects relating to details and economies of the invention will appear from the description to follow. The invention is defined and pointed out in the claims.

A preferred embodiment of the invention is illustrated in the accompanying drawing, in which:

Fig. 1 is a side perspective view of a structure embodying the invention.

Fig. 2 is a horizontal section on a line corresponding to line 2—2 of Fig. 3 with the filing spindle and base omitted, the combined punch head and guard being shown in retracted position by full lines and in operative position as a guard by dotted lines.

Fig. 3 is a fragmentary view partially in vertical section on line 3—3 of Fig. 2 with the combined punch head and guard shown in elevated position by full lines and in guard position by dotted lines.

Fig. 4 is a fragmentary view in section on a line corresponding to line 4—4 of Fig. 2 showing details of the punch and its mounting.

The embodiment of the invention illustrated comprises a base 1 preferably in the form of a circular casting and having a raised central portion 2. The base is preferably provided with a non-metallic facing 3 secured to the bottom thereof as by means of an adhesive indicated at 4.

The filing spindle 5 is centrally positioned on the raised portion 2 of the base. At one side of the filing spindle 1 mount a post 6 which extends above the plane of the tip of the spindle.

The combined guard and punch head 7 is provided with a downwardly facing socket 8 slidably and rotatably receiving the upper end of the post. The post is provided with a flattened forwardly inclined surface 9 on its front side or side adjacent the spindle, this surface constituting a guideway for the pin 10 arranged transversely through the socket of the head. The engagement of this pin with the forwardly inclined guide surface insures that the punch head is accurately aligned with the spindle to serve as a guard therefor and

also to align the punch plunger with the spindle and it prevents swinging of the punch head when it is in lowered position.

The pin is arranged transversely through the socket to properly engage this flattened surface when the head is in guard position.

At the upper end of the guide surface 9, the post is provided with a peripheral groove or recess 11 adapted to receive the pin when the head is in elevated position. The bottom of the groove constitutes a supporting shoulder for the pin. The post has a cylindrical portion 13 at the top so that the pin serves to retain the head on the post.

15 The recess 11 preferably extends around the post so that the head may be swung clear of the spindle and to position it as a guard or punch it is only necessary to swing it around into approximate alignment with the spindle and the 20 pin sliding down the guideway completes the alignment.

The punch plunger 14 is reciprocatingly mounted in the vertical bore 15 in the swinging end of the head. A coiled spring 16 seating on the 25 shoulder 17 acts to yieldingly support the plunger in retracted position.

The punch has a recess 18 in its lower end adapted to receive the end of the spindle so that papers may be placed over the end of the spindle and the plunger actuated to force them onto the spindle. When it is desired to remove the papers, the punch head is lifted and swung to retracted position as shown by full lines in Fig. 2 and the papers may be stripped off from the spindle. The punch head in operative position serves as an effective guard for the spindle as well as a support for the punch.

I have illustrated and described my invention in a highly practical commercial embodiment thereof. I have not attempted to illustrate or describe certain modifications and adaptations which I contemplate as it is believed that this disclosure will enable those skilled in the art to embody or adapt the invention as may be desired.

Having thus described my invention, what I claim as new and desire to secure by Letters Patent is:

1. A combined filing spindle, punch and spindle guard comprising a base, a spindle mounted thereon, a post mounted on said base at one side of said spindle and projecting above the plane of the tip of the spindle, said post having a flattened forwardly inclined guide surface on its side adjacent the spindle, and a peripheral groove at

the top of said flattened surface, a punch head having a downwardly facing post receiving socket, a pin on said head disposed transversely through said socket and slidably engageable with the said flattened side of the post when the head is in vertical alignment with the spindle and swingable into said groove when the head is in elevated position, the bottom of the groove constituting a shoulder for swingably supporting the punch head when it is in elevated retracted position, the pin serving to retain the punch head on the post, the downwardly inclined flattened surface acting to align the head with the spindle, a punch reciprocatingly mounted in the swinging end of the head to align with the spindle when the pin is in engagement with the flattened surface of the post, and a retracting spring for said punch.

2. A combined filing spindle, punch and spindle guard comprising a base, a spindle mounted thereon, a post mounted on said base at one side of said spindle and projecting above the plane of the tip of the spindle, said post having a flattened guide surface on its side adjacent the spindle; and a recess at the top of said flattened surface, a punch head having a downwardly facing post receiving socket, a pin on said head disposed transversely through said socket and slidably engageable with the said flattened side of the post when the head is in vertical alignment with the spindle and swingable into said recess when the head is in elevated position, the bottom of the recess constituting a shoulder for swingably supporting the punch head when it is in elevated retracted position, the pin serving to retain the

punch head on the post, and a punch reciprocatingly mounted in the swinging end of the head to align with the spindle when the pin is in engagement with the flattened surface of the post.

3. A combined filing spindle, spindle guard and punch comprising a base, a spindle mounted thereon, a post mounted on said base at one side of the spindle and projecting above the plane of the tip of the spindle, a punch head mounted on said post for swinging and vertical adjustment, said post having an annular recess adjacent its upper end and a noncircular portion extending downwardly from said annular recess for a substantial distance, said punch head having an element vertically slidably engageable with said non-circular portion when the punch head is in vertical alignment with said spindle, said element being engageable in said annular recess to permit lateral adjustment of the punch head when in elevated position relative to said spindle, said annular recess swingably retaining the head in its elevated position until it is returned into vertical alignment with the spindle, and a punch reciprocatingly mounted on the head to coact with said spindle.
